UNITED STATES PATENT OFFICE.

ALVIN N. FORLER AND RENEL W. LANGS, OF MOOSE JAW, SASKATCHEWAN, CANADA.

OIL BURNER.

1,403,398.

Specification of Letters Patent. Patented Jan. 10, 1922.

Application filed March 22, 1921. Serial No. 454,529.

To all whom it may concern:

Be it known that we, ALVIN NEIGARTH FORLER and RENEL WALDARF LANGS, both subjects of the King of Great Britain, and residents of the city of Moose Jaw, in the Province of Saskatchewan, Dominion of Canada, have invented certain new and useful Improvements in Oil Burners, of which the following is a specification.

10 This invention relates to oil burners, and has for its objects to provide a burner that can be used to heat an ordinary range or a furnace, to provide means whereby the supply of air can be mixed with the vaporized oil, to provide a means of heating ranges and furnaces with coal oil without incurring the dangers usually incurred in using coal oil for such purposes, to provide an oil burner that is simple in construction and 20 not liable to go out of repair, and generally to adapt the several parts to better perform the functions required of them.

With the above and other objects in view, the invention consists essentially of the improved construction and arrangement of parts particularly described and set forth in the following specification and accompanying drawings forming part of the same.

In the drawings;

30 Figure 1 is a perspective view of a cooking range, with the burner and fuel supply attached thereto.

Figure 2 is a perspective view of the burner alone.

35 Figure 3 is a longitudinal section through the burner.

Figure 4 is a cross section through the same.

Like characters of reference refer to like 40 parts in the several figures.

Referring to the drawings; A represents a range of usual construction provided in the fire box thereof with transversely extending rails 10 designed to carry the burner B.

45 The burner B is formed of a boxing 11 substantially rectangular in form and provided with pointed ends.

The walls 12 of the burner slant inwardly 50 as shown in Figure 4, and have a central projection 13 curved inwardly.

The top wall 14 of the burner is provided with central projections 15 adapted to form together with the projections 13 suitable air 55 feeds.

The burner proper consists of a pipe 16

extending within the rectangular casing 11 and connected by an elbow 17 to a U-shaped pipe 18 extending vertically above the casing 11 and having its end connected by an 60 elbow 18 to the horizontal pipe 19 provided with orifices 20 through which the fuel can be ejected and lighted.

The U-shaped pipe 18 carries a spreader 21 located above the jet 20 in order to 65 spread the flame of the fuel burning from the jet.

A plate 22 is carried by the casing 11 and extends under the same intermediate of the length thereof, thus leaving two under 70 openings 23 through which air can circulate upwardly and be fed to the vaporized oil through the air feeds 15. This heats air properly before mixing with vapor of oil.

The pipe 16 is connected by means of a pipe 75 connection 24 to a T fitting 25 carried by a pipe 26 supported by the range A. The pipe 26 carries a second T fitting 27 to which is connected a tubing 28 designed to convey the oil from a tank 29. The pipe 26 is provided with a needle valve 30 designed to 80 regulate the feed of oil from the tubing 28.

The fuel tank 29 is connected by means of the hollow brass wire tube 31 to a hand air pump 32 and the tank further carries a 85 gauge 33 designed to register the air pressure fed therein.

When in use the needle valve 30 is open and a little oil comes up by air pressure that has been pumped into tank into the connection 24 and fed therefrom to the distributing pipe 19, where it is lighted on its outlet through the opening 20.

More oil is then pumped and on its passage through the U-shaped pipe 28, will be 95 heated by the jet 20 impinging on the spreader 21 and will thus be vaporized on its outlet from the orifices 20.

It will be obvious that this method of using oil for fuel is perfectly safe as gas is 100 used up as fast as it is made. As the fuel supply is kept in a tank, at a distance from the burner and as coal oil is not volatile and only a small amount of oil passes through the tubing 28, the dangers usually incurred 105 with this fuel are almost eliminated.

As many changes could be made in the above construction, and many apparently widely different embodiments of our invention, within the scope of the claim, constructed without departing from the spirit or scope thereof, it is intended that all mat-

ter contained in the accompanying specification and drawings shall be interpreted as illustrative and not in a limiting sense.

What we claim as our invention is:

- 5 An oil burner comprising in combination a casing formed with inwardly slanting walls having a central projection thereon, projections on the top wall of the burner adapted in combination with the side wall
- 10 projections to form air feeds, a pipe extending within the casing and connected to a U-shaped pipe extending vertically above the casing and having its end connected to a horizontal pipe on the casing and provided
- 15 with a jet therein, a spreader on the U-

shaped pipe in opposite position to said jet, a ventilating plate on the bottom of the casing, a feed pipe, pipe connections between the feed pipe and the source of fuel, means for supplying the burner with fuel, and means for regulating the flow of oil thereto.

In witness whereof we have hereunto set our hands in the presence of two witnesses.

ALVIN N. FORLER.
RENEL W. LANGS.

Witnessses:

WILLIAM LEE BOOTH,
CLO AULENE LEVEILLE.
